[57] ABSTRACT

A rotor structure having at least two radially extending rotor disks. The disks are adjacent to each other and have a knurled portion disposed on one of the disks. The disks are compressed, thereby embossing the knurled portion onto at least one of the disks to prevent relative rotational movement of the disks. Bolts are axially disposed through the disks to prevent axial movement of the disks.

FIG. 5

ROTOR STRUCTURE AND METHOD OF CONSTRUCTION

BACKGROUND OF THE INVENTION

In a gas turbine power plant, the rotor structure is comprised of compressor and turbine portions, each portion including a plurality of disks. The disks are commonly formed having annular clutch portions which comprise radially disposed teeth on each of the adjacent disks. The teeth are formed to interlock together to prevent rotational movement of the disks relative to each other and to transmit torque. The disks are held in an assembled relation by a plurality of stay rods which are longitudinally disposed through bores in the disks. This type of rotor construction is commonly known as a curvic clutch and is shown in H. O. Pederson et al. U.S. Pat. No. 2,650,017 issued Aug. 25, 1953 and assigned to the same assignee as the present invention.

While curvic clutch disks adequately transmit high torque, the devices which machine the teeth in the disks are extremely expensive. Furthermore, it is very time consuming to machine the radial teeth which form the clutch portion on the disks.

Another structure to secure the disks together to enable the rotor to transmit high torque is fitted bolt structures disposed in the disks. However, high shear stresses are introduced in the disks because of the fitted bolts. Furthermore, because of the hostile environment in which the bolts are disposed, the disks become extremely difficult to disassemble.

Keying structures have also been suggested to prevent rotation of the disks to allow the rotor structure to transmit high torque without relative movement between the adjacent disks. However, keying structures produce notches in the disks which are already highly stressed. Furthermore, close tolerances are required resulting in costly manufacturing and assembly of the rotor structure.

It would be desirable, then, to provide an inexpensive, but effective means for transmitting high torque in a rotor structure comprised of a plurality of disks and yet have relative ease in assembly and disassembly.

SUMMARY OF THE INVENTION

The following invention relates to a rotor structure for a gas turbine or compressor, the rotor structure including a plurality of radially extending disk structures. More specifically, the invention relates to the means for securing the disks to form a rotor structure which can transmit torque without relative movement of the disks.

In the first embodiment, one of the disks includes an axially extending ledge portion and the adjacent disk includes a corresponding mating surface. Either the ledge or the mating surface has a knurled portion, which under a compressive force embosses the corresponding surface on the adjacent disk. A plurality of stay bolts are axially inserted through the disk to axially secure the disks.

In a second embodiment, a ring or additional disk structure is inserted between the mating surfaces of the disks, each of the mating surfaces having a knurled portion which is embossed on the ring structure to prevent relative rotation between the disks.

In a third embodiment, a ring, or additional disk structure is inserted between the mating surfaces on the

disks, said ring structure having knurled portions on each side thereof, the knurled portions being embossed onto the respective mating surfaces of the disks.

What is disclosed, then, is a rotor construction comprising a plurality of disks, which disks are fastened together by knurled portions which allows a high torque to be transmitted in the rotor structure. No fitted bolts or key structures which introduce high shear stresses are used. Furthermore, the knurled portions are relatively inexpensive.

DESCRIPTION OF THE DRAWINGS

FIG. 1 shows a partial section view of a rotor structure formed according to the principles of the invention;

FIG. 2 is a view taken along line II-II in FIG. 1;

FIG. 3 is an enlarged sectional view, showing the knurled portion on a disk before assembly;

FIG. 4 is similar to FIG. 3, but showing another embodiment thereof; and

FIG. 5 is a view similar to FIG. 3, but showing still another embodiment thereof.

DESCRIPTION OF THE PREFERRED EMBODIMENTS

Referring to FIG. 13 there is shown a rotor structure 10. The rotor structure 10 may be used on a gas turbine or compressor, the rotor structure being comprised of a plurality of radially extending adjacent disk structures 11 and 12. Only the top half of the rotor structure 10 is shown, since it is understood that the bottom half is substantially similar to the upper half. Projecting radially outward from the disk 11 is a plurality of rotor blades 14, and correspondingly, projecting radially outward from the disk 12 is a second plurality of rotor blades 15. The rotor blades 14 and 15 have root portions 17 and 18, respectively, which are fir tree root in cross section, as best seen in FIG. 2. An annular sealing band 20 may be disposed between the disks 11 and 12 to minimize leakages therethrough.

In accordance with the principles of the invention, there is provided an axially extending ledge portion or spigot 22 on rotor disk 11, the spigot 22 axially projecting towards the adjacent disk 12 as shown in FIG. 1. On disk 12 is an axially extending protuberance or ledge portion 24, which axially extends towards rotor disk 11. The spigot 22 and protuberance 24 insure concentricity of the disks 11 and 12.

The radially outer wall 25 of the protuberance 24, as best seen in FIGS. 1 and 3, is slightly smaller than the radially inner wall 23 of the spigot 22, thereby allowing the radially outer wall 25 of the protuberance 24 to be disposed within the radially inner wall 23 of the spigot 22. However, the radially outer wall of the protuberance 24 can have a slightly larger diameter than the inner wall 23 of the spigot 22 to permit interference in assembly of the disks such as by shrink fitting or press fitting.

The mating surface 26 of the disk 11 is a radially extending wall surface, which extends from the ingress 27 of the disk to the radially inner wall 23 of the spigot 22. The corresponding axial mating surface 28 is on the axial end wall of the protuberance 24 of the disk 12. As seen in FIG. 1, the mating surfaces 26 and 28 abut each other.

As shown in FIG. 3 (the disks being shown before assembly), there is a knurled portion 30, which is annu-

larly disposed around the mating wall surface 26 on the disk 11. The knurled portion 30, as shown, is comprised of inclined ridges, but, the knurled portion may be of any well known shape. This is more readily seen in FIG. 2, which also shows a knurling tool 32 machining the annular knurling portion 30 on the mating surface 26. As is well known in the art, the process of knurling projects a portion of the material outwardly and depresses a portion of the material inwardly. Therefore, there are axial teeth-like projections extending axially from the knurled portion 30.

After knurling one of the mating surfaces, 26 or 28, the disks 11 and 12 are pressed together by any suitable means well known in the art, such as a hydraulic press (not shown). The axial projecting teeth in the knurling portion 30 are embossed upon the corresponding mating surface 28 or 26. The disks are compressed until the surfaces 26 and 28 abut each other. Because of the friction drive between the disks at the mating smooth surfaces 26 and 28, the knurled teeth portion need not be embossed too deeply into the corresponding mating surface.

A plurality of axially extending apertures 34 and 35 (FIG. 1) are disposed within the disks 11 and 12, respectively. A plurality of stay bolts 37 are inserted therethrough to lock the disks in an axial direction. A further description of the stay bolts 37 can be found in the H. O. Pederson et al. patent previously cited.

Referring to FIG. 4, there is shown a preassembled view of two adjacent disks 39 and 40. An annular ring structure or third disk 42 is disposed between the mating surfaces 44 and 45 of disks 39 and 40, respectively. The ring structure 42 is preferably made of a material somewhat softer than the disks 39 and 40. The ring structure 42 has two mating surfaces 47 and 48, the mating surface 47 corresponding to the mating surface 44 and the mating surface 48 corresponding to the mating surface 45.

A knurled portion 50 is machined onto the mating surface 44, and is concentric relative to the axis of rotation of the rotor. A second knurled portion 51 is machined onto the mating surface 45 concentric relative to the axis of rotation of the rotor. The disks 39 and 40 and the ring structure 42 are compressed so that the knurled portions 50 and 51 are embossed onto the respective mating surfaces 47 and 48, respectively. Mating surfaces 44 and 47 frictionally abut as do mating surfaces 45 and 48, the knurling portions embossed into the ring structure 42 augmenting the friction drive between the mating surfaces. Again, as in the first embodiment, any suitable means, such as stay bolts, may be used to prevent axial movement between the adjacent disks 39, 40, and 42.

Disk structures 54 and 55 are shown in a preassembled view in FIG. 5. Disposed therebetween is a ring structure or third disk 57, the disks 54, 55, and 57 being disposed adjacent to each other. The ring structure or third disk 57 is preferably made of material which is harder than the disk structures 54 and 55. A radially extending annular mating surface 59 is provided on the structure 54 and a radial extending surface 60 is provided on the axial extending protuberance of the disk structure 55. The ring structure 57 has a mating surface 61 which corresponds with mating surface 59 and a mating surface 62 which corresponds with mating surface 60 on disk 55.

In the embodiment shown in FIG. 5, a knurling tool machines a knurled portion on each of the mating surfaces 61 and 62 of the ring structure 57, the knurled portion being about mid-way between the radially outer and radially inner surfaces of the ring structure. Then, under a compressive force by any suitable means, the disk structures 54 and 55 and the ring structure 57 are compressed under sufficient force so that the mating surfaces 59 and 61 abut, and the mating surfaces 60 and 62 abut. This causes the knurled portions 64 and 65 to emboss onto the relatively softer mating surfaces 59 and 60, respectively. The knurled portions, 64 and 65, augment the friction drive already established between the respective mating surfaces 59 and 61, and 60 and 62.

Although it is desirable that the original knurled face be harder than the face onto which the knurl is to be embossed, this is not essential since a knurled portion could be imprinted on a surface of equal hardness. Furthermore, more than three disks structures can be used.

What is disclosed then is a rotor structure, comprised of a plurality of disks which are fastened together by knurled portions. The knurled portions augment the friction drive between adjacent mating surfaces to allow a high torque to be transmitted in the rotor structure. This eliminates the previously expensive process of using curvic clutches, fitted bolts and key structures.

I claim:

1. A method of forming a rotor structure comprising the steps of:
  1. providing at least two radial extending disk structures;
  2. machining a knurled portion on at least one of the mating surfaces of the disk structures;
  3. aligning the adjacent disk structures relative to each other in axial and radial directions;
  4. compressing the adjacent disk structures to emboss the knurled portion on the other disk structure;
  5. and providing means to maintain the disk structures in axial abutment.
2. The method recited in claim 1 and further including the steps of:
  1. machining a knurled portion on the mating surface of the other disk structure;
  2. providing a third disk structure;
  3. and compressing the disk structures to emboss the knurled portions onto the third disk structure.
3. A method of constructing a rotor structure for an elastic fluid utilizing machine comprising the steps of:
  1. providing first, second and third disk structures having mating surfaces thereon;
  2. machining the mating surfaces of the third disk structure to provide annular knurling portions thereon;
  3. positioning the third disk structure between the first and second disk structures;
  4. compressing the disk structures to emboss the knurled portion of the third disk structure onto the mating surfaces of the first and second disk structures; and
  5. securing the disk structures in an axial direction to prevent axial movement between the disk structures.
